UNITED STATES PATENT OFFICE.

ALFRED F. TEITSCHEID, OF WHARTON, NEW JERSEY.

FUSE FOR PROJECTILES.

Application filed October 10, 1928. Serial No. 311,632.

The subject of this invention is a fuse for projectiles.

The object of the present invention is to provide a combination instantaneous and delayed action fuse in which detonation may be permitted axially thereof and whose structure is of such a character that the elements entering in the formation of the fuse container may be loaded as units and then readily assembled.

With the foregoing and other objects in view, my invention resides in the novel arrangement and combination of parts and in the details of construction hereinafter described and claimed, it being understood that changes in the precise embodiment of the invention herein disclosed may be made within the scope of what is claimed without departing from the spirit of the invention.

20 A practical embodiment of the invention is illustrated in the accompanying drawing, wherein:

Fig. 1 is a longitudinal sectional view through the improved fuse;

25 Fig. 2 is a detail view on the line 2—2 of Fig. 1.

Referring to the drawing by numerals of reference:

The fuse container comprises essentially 30 four elements, namely a base 5, a head 6, a body 7 to which the base and head are attached and a booster casing 8 secured to the base. The body 7 is a hollow member whose ends are tapped to threadedly receive the base and the head which are formed with shoulders, respectively 9 and 10 to seat 35 against the ends of the body and form an unbroken profile of the fuse container. The inner portions of the base and head are formed into tubular extensions, respectively 11 and 12, the former fitting into the latter and establishing a flash tube. The extremities of the extensions are unconfined so that the shock on impact will be taken by the 40 body 7 and will not cause disruption of the flash tube.

The head 6 carries a complete instantaneous firing mechanism comprising an impact striker 13 and a primer detonator 14 retained by a plug 15 threaded in the extension 12. The striker is held safe by a shear pin 16 and also by means of a centrifugally 50 releasable locking device comprising half blocks 17 interposed between the striker head 55 and the forward face of the fuse head and encircled by a tape 19 having a weighted

end 20. Release and removal of the tape and blocks is prevented by a cap 21 threaded to the fuse head. The cap is only removed when the fuse is to be functioned through 60 the instantaneous firing mechanism.

The base member 5 of the fuse is formed with a cavity 22 in its rear portion through which an axially disposed detonator 23 and an eccentrically disposed primer 24 are inserted in place in the base forwardly of the cavity. Communication between the primer and detonator is established by a transverse passage 25.

Mounted in the cavity 22 is a carrier 26 having an enlarged annular head 27 threaded to the base and a reduced cylindrical portion 28 which seats on the floor of the cavity and retains the detonator 23 in place. The carrier is formed with an axial 75 passage in which may be placed a column of explosive 29. An annular plunger 30 is mounted on the reduced portion 28 of the carrier and is normally held in the unarmed position against the head 27 of the carrier 80 by a spring 31 and also by a centrifugally releasable pin 32. For the purpose of holding the plunger against the action of its spring prior to assembling the carrier, a headed bolt 33 is passed through the plunger 85 and threaded into a prepared aperture in the base. This likewise insures a correct alinement with the primer 24 of a firing pin 34 fixed in the plunger and preferably having its point introduced into a guide 90 plug 35 adjacent the primer. The bolt 33 and the firing pin 34 thus prevent rotary movement of the plunger when it is displaced forwardly on impact. The pin 34 and primer 24 constitute the delay firing 95 mechanism.

The booster casing 8 is threaded into an annular extension 36 of the base until brought up against the carrier 26. The casing 8 carries a booster charge 37 and a pivotally mounted rotor 39 which functions in an accepted manner during flight to position a detonator 40 axially of the fuse.

From the foregoing it will be clear how the head and base may each be loaded with one of the firing mechanisms, and the fuse assembled by threading these elements to the body 7 and then finally attaching the booster casing.

I claim:

1. In a fuse, a hollow body, a head attached to one end of the body, a base at-

tached to the other end of the body, said base formed with a tubular extension on its inner portion and a cavity in its outer portion, a detonator disposed axially in the base, 5 a carrier attached to the base and disposed in the cavity thereof, said carrier having a reduced portion retaining the detonator, an axial explosive train in the carrier, an annular plunger embracing the reduced portion 10 of the carrier, a firing pin carried by the plunger, a primer carried by the base adjacent the detonator and having communication with the foremost part of the detonator, a booster casing secured to the base in rear 15 of the carrier and an instantaneous firing mechanism mounted in the head.

2. In a fuse, a hollow body, a head attached to one end of the body, a base attached to the other end of the body, said 20 base formed with a cavity in its outer portion, a detonator disposed axially in the base, a carrier attached to the base and disposed in the cavity thereof, said carrier having a reduced portion, an annular plunger embracing the reduced portion of the carrier, a firing pin carried by the plunger, a primer carried by the base adjacent the detonator and having communication with the foremost part of the detonator, a booster casing 25 secured to the base in rear of the carrier and an instantaneous firing mechanism mounted in the head.

3. In a fuse, a hollow body, a head attached to one end of the body, a base attached to the other end of the body, said 30 base formed with a cavity in its outer portion, a detonator disposed axially in the base, a carrier attached to the base and disposed in the cavity thereof, said carrier having a reduced portion, an annular plunger embracing the reduced portion of the carrier, 35

a firing pin carried by the base adjacent the detonator and having communication with the foremost part of the detonator.

4. In a fuse, a hollow body, a head attached to one end of the body and having a tubular extension, a base attached to the other end of the body and having a tubular extension engaging with the extension of the head, the ends of the extension being unrestrained, an instantaneous firing mechanism in the head and a delay firing mechanism in the base. 45 50

5. In a fuse, a body, a head attached to one end of the body, a base attached to the other end of the body, the adjacent ends of the head and base cooperating to form a flash tube, a firing mechanism carried by the nose and a firing mechanism carried by the base. 55 60

6. In a fuse, a casing formed with a cavity, a detonator disposed axially in the casing, a carrier attached to the casing and disposed in the cavity thereof, said carrier having a reduced portion retaining the detonator, an axial explosive train in the carrier, an annular plunger embracing the reduced portion of the carrier, a firing pin fixed in the plunger and a primer carried by the casing adjacent the detonator and having communication with the detonator. 65 70

7. In a fuse, a casing formed with a cavity, a detonator disposed axially in the casing, a carrier attached to the casing and disposed in the cavity thereof, said carrier having a reduced portion, an annular plunger embracing the reduced portion of the carrier, a firing pin fixed in the plunger and a primer carried by the casing adjacent the detonator and having communication with the detonator. 75 80

ALFRED F. TEITSCHEID.
